AEROSOL APPARATUS USING COMPRESSED AIR OR GASES FOR LIQUID AND POWDER PRODUCTS

Alessandro Spalazzi and Alexander Morgante, Rome, Italy, assignors to Common Market Associates Inc., Springfield, Mass.

Filed Sept. 30, 1963, Ser. No. 312,731

3 Claims. (Cl. 222—82)

Our invention relates to new and useful improvements and structural refinements in aerosol apparatus operable with a compressed gas or gases or air for the ready dispensing of any of a plurality of products of a chemical, cosmetic, pharmaceutical or like nature in liquid, powder or micropowder form.

It will be helpful to an understanding of our invention first to briefly consider some of the essential points and more important features and aspects thereof, so that same may be kept in mind during subsequent reading of the detailed description of the practical embodiments thereof and the illustrations thereof in the hereunto annexed drawing.

Accordingly, it is first to be noted that our invention may be embodied in any device for the dispensing of a liquid or powdered material.

Without intending to place undue limitations upon the scope of the invention beyond what may be required by the state of the prior art, the particular embodiment may be briefly described as embracing the concept of multi-containers for the storage in separated compartments of the propelling gas medium, known as the gas phase, and the material to be dispensed, known as the liquid or powder phase, as the case may be, preliminarily to being admixed and dispensed in a spray form, with the volatile propellant functioning to propel the liquid or powder product outwardly of the structure and may, in certain circumstances, act to modify the physical state of the product as it emerges from the container, as by expanding it into a foam or lather.

The invention comprehends hermetically sealed packages of self-propelling pressure liquid or pressure powder compositions equipped with specially designed valving mechanisms from which application is made in the form of an atomized spray.

More particularly, this invention relates to constructions for propelling mixtures of a gas and a liquid, or of a gas and a powder, through specially designed valving mechanisms, as finely atomized sprays.

The invention is characterized by the fact that the apparatus is formed of a pair of containers, one of which is adapted to contain a compressed gas or air, and the other of which contains the product to be dispensed as by spraying in the case of a material in liquid form and as by dispensing in the case of a material in powder form, the gas and the product being retained in non-communicating relationship as to each other until the moments of admixing and spraying or dispensing thereafter.

As one advantageous embodiment, by the means hereof, the compressed air or gas is not in contact with the product during storage and until immediately prior to use, it being known that, in the case of certain thereof, reactions ensue when same are exposed thereto so as to effect deleterious composition changes, which changes, it will be observed ensue at an accelerated rate when the gaseous component is under compression.

The practice of employing inert gases in the effort to preclude these aforesaid reactions or changes has been known, but the costs thereof have been so prohibitive as to discourage use thereof on any large commercial scale.

The invention is intended to provide simple and effective means for economically performing its functions while

2

also making provision for convenient and safe transportation when filled, or partly filled, without danger of content leakage.

The invention is predicated upon the use, in addition to the fluid or powder contents of the package, of valving devices in intercommunicating conduits in such relation as to receive, mix and dispense the package contents in a manner assuring the formation of a highly effective spray.

In one form, the valve device comprises a mixing chamber connected through separate orifices with the liquid and vapor phases in the container, and valves proper which control release of gas from the gas chamber and liquid or powder from the liquid or powder chamber and release of the mixture from the mixing chamber through a discharge spray orifice. Using this type of mixing and valve arrangement, and by control of orifice sizes, it is possible to achieve a pre-mixing of the liquid or powder and gaseous phases from the container that will result in release of the liquid or powder phase, in a finely atomized spray.

The invention comprehends particular constructions arrangements, combinations, and relationships of various elements, components and instrumentalities of aerosol apparatus as exemplified in the following detailed disclosure wherein the objects hereof, as defined in the above paragraphs, will be apparent.

The invention offers the advantage that one of a plurality of volatile products can be interchanged, at will with one of a plurality of materials desired to be dispensed for a particular purpose by the fact of their being contained within separable containers each interfitting a common joint containing the cooperant means for effecting delivery of the respective products to a main mixing chamber for admixing preliminarily to discharge therefrom as an atomized spray.

To make the manufacture of such apparatus a more profitable undertaking, the mechanism embodying the essence of the invention has been engineered in manner as to be simple in its construction so as to expedite economical large-scale production and assembly with a minimum of tooling, the usual complexity of components having been so greatly reduced as to offer a compact design representative of a fundamentally new concept in the combining and coating of aerosol apparatus parts.

Precision of relative dimensioning of parts as militates against inexpensive manufacture, simplicity of maintenance and care, and consistency of performance in practical use have been assiduously borne in mind in the development of the present invention.

Too, we provide apparatus of the above-mentioned character in which ruggedness and durability of construction are combined with simplicity of protection against usual but hard conditions of practical use and with simplicity and ease of use.

Further, while the components are uniquely compact, they are nevertheless readily accessible for maintenance and replacement purposes with a consequent reduction in maintenance costs over related devices heretofore known.

To provide apparatus which effectively meets the requirements therefor and perform its functions in a practical and dependable manner is among the dominant aims of this invention.

Other of the chief objects and purposes hereof are to provide advantageous structural and operational features in devices of the class to which reference has been made so as to offer an apparatus having the following inherent meritorious characteristics; first, engineeringwise, a uniqueness in design of coating parts wherefor the components are coordinated for facile assembly and, when once assembled, are positively and securely retained in operative relationship so as to be not readily separable from each other, accidentally or otherwise; second, a high

degree of efficiency and dependability in its operational use; third, the attainment of a convenience of arrangement of parts and a flexibility or a capability of adjustment by which a large variety of work can be produced by means of the same device; and fourth, the provision of constructions which are well adapted to withstand the usage to which such devices are ordinarily subjected.

Further objects are to provide aerosol apparatus conformable to the desiderata of the preceding paragraphs and offering specific improvements in its various operating instrumentalities, which themselves are minimum in number, so that it is simple and compact in accordance with the demands and desires of manufacturers and purchasers alike and so as to provide distinct advantages in that it is distinctive in its appearance, practical in its value, durable in its organization, reliable in its operation, and efficient in its use.

To the end of attaining these objects and advantages and others hereinafter reasonably appearing, it will be explained that the invention consists substantially in the combinations, constructions, locations and functions of parts, as herein described in detail.

It will be apparent, however, that the physical embodiments delineated, albeit the preferred exemplifications, are only indicative of but several of the multiplicity of ways in and purposes for which the principles of the invention may be employed. Same are submitted as best known embodiments of the invention in accordance with the patent statutes and are given with a view to illustrating and explaining the precise nature of the principles of the invention and their embodiments for practical use, in order that others skilled in the art to which the invention pertains may be enabled to adapt and modify them in other reasonable variations and modifications, each as may be best adapted to the conditions of any particular use.

The invention reverted to is not restricted or confined to said embodiments and same are not intended to be exhaustive of, nor limiting of, the spirit or scope hereof. That is, the precise construction of the figures of the drawing need not be slavishly followed as, of course, the devices may have to be adapted or alternatively constructed or modified in accordance with any specific use contemplated therefor. Such adaptations and/or alternative constructions and/or modifications are intended to be comprehended within the meaning and purview and range of equivalence of the below subjoined claims, there being no intent to have this invention limited to or circumscribed by any specific details.

The objects of the invention are susceptible of attainment by use of constructions different in certain respects from those disclosed, such as minor changes and variations in dimensions, shapes and the like, all without departing from the underlying scope and spirit hereof.

The characteristic features which we consider to be novel with our invention will be better understood from a consideration of the following detailed description forming a part of this specification, when read in conjunction with the illustrations in the accompanying drawing, in which:

FIG. 1 is a top plan view illustrating the apparatus of the invention in a refillable-liquid dispensing form;

FIG. 2 is a sectional view through the midsection of the apparatus shown in FIG. 1;

FIG. 3 is a top plan view illustrating the apparatus of the invention in another form delineated the refillable-liquid or powder dispensing form;

FIG. 4 is a sectional view through the midsection of the apparatus shown in FIG. 3;

FIG. 5 is a sectional view through the midsection of another form of the apparatus of the invention delineated the non-refillable liquid or powder dispensing form; and

FIG. 6 is an exploded top plan view of the form of the apparatus shown in FIG. 5.

In the practice of the invention, according to FIGS. 1

and 2 of the drawing, we have shown a construction of one form thereof, delineated a refillable apparatus for the dispensing of liquids, same being constituted by an enclosed compressed air or gas container 1, for containing the gaseous phase, and an open-ended liquid container 2, for containing the liquid phase, and held relative to container 1 as by an annular common joint 3.

Containers 1 and 2, preferentially, though not obligatorily, are each of generally elongated cylindrical configuration having a rounded closed end at its outboard extremity.

Container 1, at its inboard extremity, is provided with a neck of reduced diameter with an opening through said neck allowing communication between the container interior and exterior thereof.

Container 2, at its inboard extremity, is provided with an open end to allow an opening substantially the diameter of the cylinder wall.

Joint 3 is of a configuration such as to allow, at its gas-compartment face, an annular noselike or cuplike or semispherical shoulder recess of a configuration accommodating itself to the outer configuration of the annular shoulder of container 1, and an annular neck recess concentric with and extending inwardly away from the bottom of the shoulder recess, said neck recess being of a configuration accommodating itself to the outer configuration of the annular neck of container 1, wherefor the container is adapted to be frictionally engaged with joint 3 so as to hold the components stationarily as to each other during operative use.

Joint 3 is additionally configured at its liquid-compartment face with a peripheral recess for receiving, as by a frictional fit, the inboard end portion of the open ended container 2, wherefor said container is likewise adapted to be held stationarily relative to the joint during operative use.

It follows that various combinations of containers 1 (containing different volatile products) and containers 2 (containing different liquids) can be constituted with a common joint 3 for the specific purposes envisioned.

In operative position as to each other, containers 1 and 2 and joint 3 will be observed to be held in co-axially aligned relationship with their outermost peripheral surfaces being coplanar as to each other so as to present a smooth, uninterrupted outermost contour wherewith the composite structure may be readily manually grasped, easily transported, and conveniently stored.

A valve 4 of generally T-shaped configuration is disposed relative to container 1 wherefor its transversely-positioned head portion is receivable within the container while its stem or shank portion 5 is extendable outwardly of the container through a suitable valve stem opening extending through a valve seat 6 which is tightly fitted into the opening of the neck of the container and also through a concentrically-arranged annular gas conduit 14 communicating with the annular neck recess.

Joint 3 is additionally provided with an annular liquid conduit 7, disposed in a plane parallel to and non-coaxial with the axis of gas conduit 14.

Said liquid conduit 7 communicates with liquid container 2 at its outboard extremity and at its inboard extremity intersects and communicates with the cone shaped inner end wall of an enlarged annular passageway having a main axis transversely-disposed relative to liquid conduit 7 and to gas conduit 14 which also at its inboard extremity intersects and communicates with the said passageway.

Coaxial with the main axis of the enlarged passageway and communicating therewith at its point of intersection at the apex of the cone shaped inner end wall of said enlarged passageway is the inboard terminus of an annular main or mixing chamber 15. The outboard terminus of said main chamber is at the outermost peripheral surface of joint 3 in the manner of a nozzle.

A valve 8, having the configuration of a pair of cones

arranged in back-to-back relationship, is reciprocable within the enlarged passageway in directions coincident with the main axis thereof between valve-closed and valve-opened positions.

In valve-closed position, the outboard conical surface of valve 8 seats upon the cone shaped inner end wall of the enlarged passageway in manner to seal off egress of any materials through mixing chamber 15.

In movement toward valve-opened position, achieved via means to be defined, the inboard conical surface of valve 8 functions in camlike manner to engage with the inboard free extremity of the stem or shank portion 5 of valve 4 and to drive same inwardly relative to container 1 so as to effectuate the valve-opening of said valve 4.

Valve 8 is influenced into normal valve-closed position by a means inclusive of a valve stem 11 unitary with and extending away from valve 8 in a direction coaxial with the main axis of the enlarged passageway, a spring 10 which is sleeved upon said valve stem in a circumscribing manner and has an inboard extremity confrontable with and bearing upon the adjacent face of a washerlike member 9 sleeved upon and stationarily fixed to said valve stem in transverse relationship and has an outboard extremity confrontable with and bearing upon the adjacent face of a closure plate 12 nestably receivable within the enlarged passageway for enclosing same adjacent the outer peripheral surface of joint 3.

A control member 13 is pivotally engaged with valve stem 11 adjacent its outer free extremity which is extendable outwardly of joint 3 through a suitably provided opening through and centrally of closure plate 12.

Control member 13 serves to effectuate motivation of valve 8 by the retraction thereof away from its normal seating against the inner end wall of the enlarged passageway into valve-opened position against the resistance of spring 10 so as to open in seriatim main or mixing chamber 15 and liquid conduit 7 as the valve withdraws away from the inner end wall, and further in seriatim to open gas conduit 14 by so camming the stem of valve 4 as to effectuate the unseating of the head portion of said valve from its normal valve-closed position upon valve seat 5.

The opening of gas conduit 14 permits the release of the gaseous phase product at high speed from within container 1 through gas conduit 14 and into the enlarged passageway and thence outwardly through main or mixing chamber 15, passing the opening of liquid conduit 7 in this travel.

As the gaseous product is wiped past liquid conduit 7, the liquid product is induced by suction from within container 2 through said liquid conduit and along the end wall of the enlarged passageway and thence outwardly through main or mixing chamber 15 where it is admixed with the gaseous product in manner sufficient to allow atomization of the liquid product and dispersal therefrom through the outer nozzle end of the main chamber.

Release of control member 13 serves to effectuate the return of valve 8 to valve-closed position.

In the embodiment of the invention, according to FIGS. 3 and 4 of the drawing, we have shown a construction of a form, delineated a refillable apparatus for the dispensing of liquids or powder products, same being constituted by an enclosed compressed air or gas container 1', for containing the gaseous phase, and an open-ended liquid or powder container 2', for containing the liquid or powder phase, and held relative to container 1' as by an annular common joint 3'.

Each of containers 1' and 2', preferentially, are of generally elongated cylindrical configuration with a closed end of ovoid shape at its outboard extremity.

Container 1', at its opposite inboard extremity, is configured to define a neck of reduced diameter having an opening therethrough for ingress to and egress from the container interior while container 2', at its inboard extremity, is configured to allow an open end defining an opening substantially the diameter of the cylinder wall and is provided additionally with a transversely-extending

membranous diaphragm 17 serving to divide container 2' into an inner liquid or powder storage chamber and an outer expansion chamber 18, for purposes as will appear.

Joint 3' is configured, at its gas-compartment face, with 5 an annular semispherical shoulder recess to accommodate in tight-fitting manner the annular shoulder of container 1'. In communication and concentric with and extending inwardly from said shoulder recess, an annular neck recess is provided, same having a configuration accommodating itself to the neck of container 1'. Thus, container 1' is adapted to be frictionally engaged with joint 3'.

Additionally, joint 3' is configured at its liquid or powder compartment face with a peripheral recess for frictional engagement of the inboard open end portion of 15 container 2' so as to define an enclosing wall of expansion chamber 18.

In operative position as to each other, containers 1' and 2' and joint 3' are in co-axially aligned coplaner relationship.

20 A T-shaped flat valve 4' has a transversely-disposed head portion which is receivable within the container and a stem or shank portion 5' which is extendable outwardly of the container through a suitable valve stem opening extending through a valve seat 6' tightly fitted into the opening of the neck of the container and also through a concentrically-arranged annular gas conduit 20 in joint 3' and communicating with the annular neck recess.

Joint 3' is additionally provided with an annular liquid/powder conduit 7' which communicates with expansion chamber 18 at its inboard terminus and with the atmosphere at its outboard terminus at the outer peripheral surface of joint 3'.

Said liquid/powder conduit is generally L-shaped in configuration.

35 The joint 3' is still further provided with an enlarged annular passageway having a main axis which is transversely-disposed relative to gas conduit 20 which at its inboard extremity intersects and communicates with said enlarged passageway.

40 A cam 16, which may be of generally conical configuration, is reciprocable within the enlarged passageway in directions coincident with the said main axis thereof between valve-closed and valve-opened positions.

In valve-closed position, cam 16 seats upon the inner end wall of the enlarged passageway.

45 In movement toward valve-opened position, achieved via means about to be defined, the conical surface of cam 16 in camlike manner confronts the inboard free extremity of stem or shank portion 5' of valve 4' and as the cam 50 moves toward valve-opened position, to drive same inwardly relative to container 1' thereby to effectuate a concomitant valve-opening of said valve 4' by causing the retraction of the head portion thereof away from contacting relation with valve seat 6' in its valve-closed position.

55 Cam 16 is influenced into normal valve-closed position by a means inclusive of a stem 11' unitary with an extending away from cam 16 in a direction coaxial with the main axis of the enlarged passageway, a spring 10' circumscribing said stem and having an inboard extremity confrontable with and bearing upon the adjacent face of a washerlike member 9' sleeved upon and stationarily fixed to said stem in transverse relationship and having an outboard extremity confrontable with and bearing upon the adjacent face of a closure plate 12' nestably receivable within the enlarged passageway for enclosing same adjacent the outer peripheral surface of joint 3'.

A control member 13' is pivotally engaged with stem 70 11' adjacent its outer free extremity which is extendable outwardly of joint 3' through a suitably provided opening through and centrally of closure plate 12', and serves to effectuate retraction of cam 16 away from its normal seating against the enlarged passageway inner end wall and 75 into valve-opened position against the resistance of spring

10' so as to open gas conduit 20 by the camming of stem 5' of valve 4', as aforesaid.

As the volatile gaseous product exists container 1' with high speed via gas conduit 20 and into the enlarged passageway, and therefrom, it passes through the conduit of a needle 19 which extends through a suitable opening in joint 3' with one extremity disposed in the plane of the wall of the enlarged passageway and an opposite extremity extendable outwardly therefrom.

Upon assembly of liquid powder container 2' upon joint 3', needle 19 is caused to be penetrated through diaphragm 17 so as to rupture the diaphragm. Thus, it will be observed that the gaseous product passes with high speed through the needle and into the liquid or powder storage.

As the gaseous product passes into the liquid or powder storage chamber of container 2', it creates a turbulence therewithin.

The generated turbulence is such as to induce the product to be discharged from within the liquid or storage chamber to the expansion chamber of container 2', through said conduit 7', and thence to be discharged therefrom through the outer nozzle end.

In the embodiment of the invention according to FIGS. 5 and 6 of the drawing, we have shown a construction of one form thereof, delineated a non-refillable apparatus for the dispensing of liquids or powders, same being constituted by an enclosed compressed air or gas container 1A, for containing the gaseous phase, and an open-ended liquid or powder container 2A for containing the liquid or powder phase, and held relative to container 1A as by an annular joint 3A.

Containers 1A and 2A are each of generally elongated cylindrical configuration having a rounded closed end at its outboard extremity.

Container 1A, at its inboard extremity, is provided with a neck of reduced diameter with an opening through said neck allowing communication between the container interior and exteriorly thereof.

Container 2 is similarly configured.

Joint 3A is of a configuration such as to allow, at each of its opposite faces, an annular semispherical shoulder recess of a configuration accommodating itself to the annular shoulder of the respective container 1A or 2A and concentric with and extending inwardly from the bottom of the shoulder recess an annular neck recess of a configuration accommodating itself to the annular neck of the respective container 1A or 2A, wherefor each container is adapted to be frictionally engaged with joint 3A.

In operative position as to each other, containers 1A and 2A and joint 3A are held in coplanar coaxially aligned relationship.

It is here to be explained that, in this form of the invention, containers 1A and 2A will not be assembled into said operative position until the moment of their use.

An annular nozzle conduit 15A is provided in joint 3A which communicates at its inner terminus with the opening within the neck of container 2A and at its outer terminus with the atmosphere through the outer peripheral surface of the joint.

A conduit needle 23 is disposed along the main axis of containers 1A and 2A having one terminus extending through a rubber cap 22 in the opening in the neck of container 1A and an opposite terminus extending through a transverse wall 21 in the form of a sealing diaphragm in container 2A.

When the apparatus is to be readied for operative use, container 2A is first inserted on joint 3A wherefor the sealing diaphragm 21 is ruptured by conduit needle 23.

Container 1A is thereafter inserted on joint 3A and conduit needle 23 is caused to pierce through rubber cap 22.

The volatile product is thus released to pass through conduit needle 23 to the interior of container 2A where

5 a generated turbulence causes the product to be admixed with the gas and to be discharged through nozzle 15A.

The components of the each assembly thereshown, almost in their entireties are advantageously and preferentially though not necessarily made of a suitable substance such as metal, although in practice the containers and other elements may be formed from glass or plastic or any equivalent material compatible with the purposes of my invention or other material having similar physical characteristics.

Other modes of applying the principles of our invention may be employed instead of those explained, change being made as regards the mechanisms herein disclosed, provided the means stated by any of the following claims or the equivalent of such stated means be employed.

It is believed that the gist of the invention will be clearly understood from the foregoing disclosure and accordingly, further analysis thereof at this point is considered unnecessary, as we have, in accordance with the provisions of the patent statutes, described the constructions and principle of operation of our invention together with the apparatus which we believe to represent the best embodiments thereof, to the end that others can, by applying current knowledge, readily adapt them for various applications without omitting features which, from the standpoint of prior art, fairly constitute essential characteristics of its generic and/or specific aspects.

20 25 30 35 40 45 50 55 60 65 70 75

The substitution of equivalents and other changes, modifications and alterations as circumstances may suggest or render expedient, are reasonably contemplated, the invention being susceptible of such without departing from its real spirit or underlying principles.

The claims are desired to include within the scope thereof all of said suitable variations, modifications and equivalents by which substantially the results of the invention may be obtained through the use of substantially the same or equivalent devices or means. Accordingly, limitation hereof should only be made as determined by a proper interpretation of the prior art and the scope of the subjoined claims, in which it is our intention to claim all novelty inherent herein as broadly as possible.

We therefore particularly point out and distinctly claim as our invention:

1. Aerosol apparatus using a compressed gas for dispensing a liquid or powder product characterized by, a primary container for containing the product to be sprayed, a secondary container for containing the compressed gaseous product, a common joint for receiving said primary and secondary containers in frictional engagement therewith, and control means carried by said common joint for effecting the release of the materials from said containers and the admixing thereof preliminarily to discharge therefrom and incorporating a double valve activated by a pivotal control for opening and closing in seriatim a nozzle and a conduit leading from said primary container and a conduit leading from said secondary container.

2. Aerosol apparatus using a compressed gas for the dispensing of liquid or powder products characterized by, a primary container for containing the product to be sprayed, a secondary container for containing the compressed gaseous product, a common joint for the mounting of said primary and secondary containers thereupon and having a discharge nozzle, and control means carried by said common joint, said primary container including a rupturable diaphragm for containing the product to be sprayed therewithin until ready for use, a needle mounted upon said common joint for rupturing the diaphragm of said primary container for effecting the release of the materials from said containers and the admixing thereof preliminarily to discharge from the discharge nozzle of said common joint, said common joint incorporating a double valve activated by a pivotal control for opening and closing in seriatim a conduit leading from said primary container and a conduit leading from said secondary container and said nozzle.

3. Aerosol apparatus using a compressed gas for the dispensing of liquid or powder products characterized by, a primary container for containing the product to be sprayed, a secondary container for containing the compressed gaseous product, a nozzled common joint for mounting said containers thereupon, said primary container including a rupturable diaphragm for containing the product to be sprayed therewith until ready for use, a needle mounted upon said common joint for rupturing the diaphragm of said primary container, and control means carried by said common joint for effecting the release of the materials from said containers and the admixing thereof preliminarily to discharge from the nozzle of said common joint and incorporating a manually acti-

5 vated double valve for opening and closing in seriatim a conduit leading from said primary container and a conduit leading from said secondary container and said nozzle.
